COMBINED LIGHT AND FIRE ALARM CASING

Alexander Merdan, New York, N. Y.

Application June 26, 1936, Serial No. 87,369

3 Claims. (Cl. 177—7)

This invention relates to new and useful improvements in a combined light and fire alarm casing.

Specifically, the invention contemplates the construction of a combined light and fire alarm casing which is characterized by a perforated body of several sections, a removable socket and lamp mounted on one of the sections, a bell mounted on another of the sections, and a thermostatic switch mounted on another of the sections.

It is also proposed to connect the lamp, the bell and thermostat to operate in a pre-requisite manner.

15 The invention has for an object a modified construction of the article as mentioned which is characterized by a bell element mounted upon a base member and associated with an electrically operated clapper mechanism arranged to function with or without a signal lamp and operated by a thermostatic switch, and particularly characterized by the provision of opposed housing sections encasing the bell element and adjustably mounted to regulate the sound emanating from the bell.

20 A further object is the provision of a tubular casing housing the clapper mechanism and supporting a socket by which the article may be engaged into a conventional electric fixture and 30 said socket being associated with said indicating lamp.

Still further the invention contemplates various arrangements for the thermostatic switch.

A further object of the invention resides in 35 the provision of a wiring system associated with a combined light and fire alarm constructed according to a modification of the invention.

For further comprehension of the invention, and of the objects and advantages thereof, reference will be had to the following description and accompanying drawings, and to the appended claims in which the various novel features of the invention are more particularly set forth.

45 In the accompanying drawings forming a material part of this disclosure:—

Fig. 1 is a side elevational view of a device constructed according to this invention.

Fig. 2 is a fragmentary sectional view of Fig. 1.

50 Fig. 3 is a transverse sectional view taken on the line 3—3 of Fig. 2.

Fig. 4 is a transverse sectional view taken on the line 4—4 of Fig. 2.

55 Fig. 5 is a transverse sectional view taken on the line 5—5 of Fig. 2.

Fig. 6 is a transverse sectional view taken on the line 6—6 of Fig. 2.

Fig. 7 is a fragmentary bottom view looking in the direction of the line 7—7 of Fig. 2.

Fig. 8 is a sectional view of the thermostatic 5 switch used in the device.

Fig. 9 is a side elevational view of a combined light and fire alarm casing constructed according to a modification of this invention.

Fig. 10 is a transverse sectional view of the device shown in Fig. 9.

Fig. 11 is a horizontal sectional view taken on the line 11—11 of Fig. 10.

Fig. 12 is a side elevational view of a device constructed according to a modification of the 15 invention, a portion thereof being broken away to disclose interior parts.

Fig. 13 is a schematic wiring diagram of a modification of the device.

Fig. 13a is a schematic wiring diagram of the 20 device shown in Figs. 9 to 11.

Fig. 14 is a sectional view taken on the line 14—14 of Fig. 12.

Fig. 15 is a sectional view taken on the line 15—15 of Fig. 12.

25 Fig. 16 is a schematic wiring diagram of a modified form of the invention.

Fig. 16a is a portion of Fig. 16 showing the device in a closed position.

Fig. 17 is a perspective view of one of the modified devices.

Fig. 18 is a sectional view taken on the line 18—18 of Fig. 16.

30 Fig. 19 is a schematic view of another modified form of the invention.

In the form of the invention shown in Figs. 1—8 inclusive there is a perforated body which consists of a top perforated section 76, a central perforated section 77, and a bottom perforated section 78 removably connected together. The 40 central perforated section 77 has a top wall 77^a and an open bottom. A lamp socket 79 is mounted on the top section and is provided with a lamp 80 extended into the section. A bell 81^b is mounted in the central section 77. A thermostatic 45 switch 82 is mounted within the bottom section 78. A circuit connects these parts as hereinafter further described.

The top section 76 is formed with a plurality of perforations 76^b. It is also formed with a 50 flange 76^c which threadedly engages on the top of the central section 77. An insulation plate 84 is mounted upon the top wall 77^a of the central section and serves to insulate the heat from the lamp 80 from reach of the thermostatic switch 82. 55

The bell 81 includes an armature 81^a which is supported from the top wall 77^a and upon the lower end of which a bell 81^b is mounted. This bell is operated by a conventional clapper 81^c and the regular make and break apparatus, not shown in detail, upon the drawings. The central section 77 is formed with a plurality of perforations 77^b. The bottom section 78 is formed with a plurality of perforations 78^b. At the top it is 5 threadedly engaged on the lower end of the central section 77. A cup shaped washer 86 is loosely rested in the open top end of the bottom section 78 and supports an inverted insulation cup 87. Within this cup there is supported a finger grip 10 bracket 88 into which the thermostatic switch 82 may be placed. These fingers are connected up in the electric circuit, as for example, by the lead 89. The cup 87 is formed with an end contact 90 which is connected with the lead 91. The 15 leads 89 and 91 extend through internal passages 92' formed along the inner wall of the top section 76.

The thermostatic switch 82 comprises a glass or other insulated receptacle having an internal 20 passage 82^a in which mercury 82^b or other expandible material is held. A link contact 89' is connected and supported by the lead 89 and it is through this link that the thermostatic switch is actuated. When in the proper position an electric conductor pin 82^c from an intermediate portion 25 of the passage 82 will connect with the link 89', and when the mercury 82^b expands sufficiently it will connect with another terminal 82^d adjustably mounted in a removable cap 82^e arranged on the top of the insulation body.

A cup 92 is supported on the bottom of the bottom section 78 by reason of having its side walls engaging therein and several screws 93 mounted through the bottom end of the section 78 engage 30 slots 94 in the wall of the cup 92. Several prongs 95 project from the bottom of the cup 92 by which it may be easily moved. The cup 92 has a central opening 96 through which the thermostatic switch 82 may be placed into position 35 and removed from position. Normally, the cup 92 is in the lowered position shown in Fig. 2. If desired, it may be manually moved upwards so that the lower end of the thermostatic switch 82 extends through the opening 96. The switch 40 may then be gripped and removed from the device.

The combined light and fire alarm, according to this invention as shown in Figs. 9 to 11, comprises a base member 10 upon which a bell alarm element 11 is mounted. An electrically operated clapper 12 is mounted on the bell element 11. A tubular casing 13 houses the clapper mechanism, as hereinafter further described. A socket 14 is mounted on the outer end of the casing 13. A thermostatic switch 15 is mounted upon the base member 10. A lamp 16 is supported on the socket 14 and is disposed within the casing 13. A circuit connects the socket, the clapper mechanism and the thermostatic switch in series, and 45 connects the lamp 16 in parallel as hereinafter further explained.

Opposed housing sections 17 and 18 are adjustably mounted on the device and encase the bell element 11. The housing section 17 is formed 50 with several elongated slots 19 through which holding screws 20 pass. These holding screws engage into the tubular casing 13. The housing section 18 is fixedly mounted on the base member 10. Each of the housing sections has several 55 off-set and enlarged portions which extend out-

wards and towards each other and which form a confined area in which the bell 11 is housed. The housing section 17 may be adjusted towards or from the section 18 so as to completely enclose the bell element, or to provide pre-determined 55 spaces through which the sound may pass.

The base member 10 is constructed of insulation material and has a closed top end 10^a and an open bottom end. The bell element 11 is secured by an insulated screw 20 to the closed top 10 10^a of the base member. This screw 20 engages through insulation washers 21 and extends upwards and connects with and supports an iron core 22 of a coil 23. This coil is included in the clapper mechanism. The clapper 12 is fixed on 15 a resilient arm 24 which is supported on the top of the coil 23. A make and break device 26 is mounted respectively upon the coil 23 and the arm 24. The section upon the arm in a drawn-in position of the clapper breaks the circuit with the 20 section supported on the core 23, and in the extended position of the arm 24 the circuit is closed.

The tubular casing 13 is also constructed of insulation material and is formed with several windows 28 through which the lamp 16 and the 25 light from the lamp may be seen. The casing 13 has its upper end formed with threads 29 which are adapted to receive complementary threads on the base portion of the socket 14. The socket is of conventional construction having an insulated end contact 30 and a metallic shell contact 31. The lamp 16 is supported upon the insulation material of this socket.

A web supporting bracket 32 is mounted upon the top of the coil 23 and is adapted to engage 35 the inner face of the tubular casing 13 for frictionally connecting these parts. The tubular casing is formed with a slot 33 through which the clapper 12 projects so that the clapper may strike against the bell. Numeral 34 indicates the electric leads of the device. It should be noted that these leads are within the device. They pass through aligned openings 35 in the bell element 11 and in the portion 10^a of the base member. Fig. 5 schematically shows the wiring arrangement.

In Fig. 13 a schematic wiring diagram of a modified form of the device is shown. A circuit 34 connects with a socket plug 31 by which the device may be plugged into a live electric circuit. 50 The circuit 34 includes in series the thermostatic switch 15 and the electric bell 11. A circuit 104 is arranged in parallel with the circuit 34 and includes in series a switch 39 and the lamp 16. The arrangement is such that when the circuit 55 34 is operating, should the thermostatic switch close due to a fire or other heat supply causing it to operate, the alarm will sound. If the switch 39 is closed the lamp 16 will be illuminated and be a visual alarm. This is a safety device should the alarm 11 fail. Fig. 13a is a wiring diagram of the form shown in Figs. 9 to 11.

The thermostatic switch 15 comprises a cap 40 which is frictionally engaged upon the base member 10. This cap is formed with a bayonet slot 41 which is engaged by a clamp screw 42 adjustably mounted on the base member 10. This clamp screw may be loosened and the cap turned for adjusting the thermostatic switch.

There is a scale 43 on a ring 43' which is fixed 70 on the base member 10 and indicates degrees at which the thermostatic switch is set. The thermostatic switch includes a heat expandible element 15^a adapted when desired to expand and engage a contact 15^b on a support 45 secured on 75

the interior of the base member 10. The heat sensitive element 15 is mounted upon a disc 46 constituting the end of the cap 40. This disc is formed with several openings 47 through which 5 the air may circulate.

One of the shoulder portions of each of the opposed housing sections 17 and 18 is formed with a plurality of apertures 50 through which the sound may pass. A control ring 51 is 10 rotatively mounted on each of the housing sections and is formed with alignable openings 50' to control the extent to which the sound may pass. Each of the annular members 51 is associated with a resilient holding means. This resilient 15 holding means comprises several studs 52 mounted upon the housing section and engaging into slots 53 formed in the annular member 51. The arrangement permits the annular member to be adjusted to control the extent of alignment of 20 the openings 50 and 50'. The dot and dash lines 54 in Fig. 9 indicate a conventional electric socket into which the plug socket 14 may be threaded engaged.

In Figs. 12, 14 and 15, a modified form of the 25 invention is disclosed which distinguishes from the prior form merely in the details of construction of the thermostatic switch. According to this form of the invention the thermostatic switch comprises a glass mercury heat sensitive 30 element 55 having an internal mercury chamber 56 which communicates with several radially projecting pins 57 adapted to make electric contact with rings 58 adjustably mounted on the exterior of the case of the switch. These rings are 35 connected in the circuit 34. A protecting shell 59 is engaged over the thermostatic switch and is mounted upon the base member 10. In other respects this form of the device is identical to the previous form and similar parts may be recognized 40 by the identical reference numerals.

The operation of the device is as follows:—

In the event of fire or for some other reason a sufficient amount of heat is generated, the thermostatic switch will operate to close the 45 electric circuit. Instantly, the clapper mechanism is set into operation and sounds the bell. The lamp 16 is illuminated if the switch 39 is closed and serves to further indicate the presence of excess heat. In order that the alarm may be 50 modulated the housing sections 17 and 18 may be adjusted to pre-determined positions so as to dampen the radiation of the sounds from the bell. If a loud alarm is desired the passage between the housing sections is increased to the 55 maximum, and in addition the openings 50 and 50' are aligned. If a toned-down sound is desired the openings 50 and 50' are straddled and the housing sections 17 and 18 are brought together.

60 In Figs. 16-19 inclusive a modified form of the invention has been disclosed in which the combined light and fire alarm device comprises an insulating casing 62 adapted to be secured down on ceilings and walls with a screw 63. From one 65 side of the casing an indicating lamp 16^a is mounted. Within each of the casings there is a thermostatic switch 15^d. These devices are connected in series by a circuit 65 which receives 70 electricity through a conventional plug 66 intended to be connected with a house or other electric circuit. The thermostatic switches 15^d are connected with each other by thermostatic element 15^{dd}. These elements are merely conductors for heat so that heat from the vicinity 75 may be conducted to the thermostatic elements.

In the normal position of each thermostatic switch 15^d the circuit 65 is open. When the thermostatic switch 15^d becomes heated it expands and extends across the open circuit 65 closing the circuit and setting the device into 5 operation. An electric bell 68 is connected in a circuit 69 connected in parallel with the circuit 65.

In Fig. 19 another form of the invention is shown in which a mercury thermostatic switch 75^d is used to operate the device. This mercury switch 10 has several live terminals 69 and 69' which are connected in a circuit 70. This circuit 70 includes the plug 71 for engaging a socket over an electric system. The bell 76 is connected in the circuit 15 70' and also in the lamp circuit 70.

The arrangement is such that when the thermostatic switch 75^d is heated the circuit 70 is closed and the bell as well as the lamp will be set into operation.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In a combined light and fire alarm casing, 30 a base member, a bell mounted thereon, a clapper mechanism coaxially mounted on said bell, a tubular casing supported on said clapper mechanism and encasing said clapper mechanism and being slightly spaced from said base member 35 forming a space through which the edge portion of said bell projects, a housing section fixedly mounted on said base member and partly encasing said bell, and a second housing section adjustably mounted on said tubular casing and 40 being adapted to cooperate with said housing-section to completely encase said bell, whereby said adjustable housing section may be adjusted and held in a fixed position in relation to said housing section to control the amount of sound that 45 will emanate from said device.

2. In a combined light and fire alarm casing, a base member, a bell mounted thereon, a clapper mechanism coaxially mounted on said bell, a 50 tubular casing supported on said clapper mechanism and encasing said clapper mechanism and being slightly spaced from said base member forming a space through which the edge portion of said bell projects, a housing section fixedly mounted on said base member and partly encasing said bell, and a second housing section 55 adjustably mounted on said tubular casing and being adapted to cooperate with said housing section to completely encase said bell, whereby said adjustable housing section may be adjusted and 60 held in a fixed position in relation to said housing section to control the amount of sound that will emanate from said device, said adjustable mounting, comprising holding screws freely passing through elongated slots in said second housing 65 section and threadedly engaging openings in said tubular casing.

3. In a combined light and fire alarm casing, a base member; a bell mounted thereon, a clapper mechanism coaxially mounted on said bell, a 70 tubular casing supported on said clapper mechanism and encasing said clapper mechanism and being slightly spaced from said base member forming a space through which the edge portion of said bell projects, a housing section fixedly 75

mounted on said base member and partly encasing said bell, and a second housing section adjustably mounted on said tubular casing and being adapted to cooperate with said housing section to completely encase said bell, whereby said adjustable housing section may be adjusted and held in a fixed position in relation to said housing section to control the amount of sound that will emanate from said device, shoulder portions 5 formed in said housing sections and having spaced 10

apertures therethrough, control rings rotatively mounted on said shoulder portions and having spaced apertures alignable with said apertures, whereby the apertures in said control rings may be positioned with relation to said apertures in said shoulder portions to control the volume of sound that will emanate from said device when said housing sections are closed. 5

ALEXANDER MERDAN. 10
